UNITED STATES PATENT OFFICE.

NIS S. NISSEN, OF RACINE, WISCONSIN.

BOX-COVER BRACE AND SUPPORT.

SPECIFICATION forming part of Letters Patent No. 611,018, dated September 20, 1898.

Application filed September 13, 1897. Serial No. 661,460. (No model.)

To all whom it may concern:

Be it known that I, NIS S. NISSEN, a citizen of the United States, and a resident of Racine, in the county of Racine and State of Wisconsin, have invented certain new and useful Improvements in Box-Cover Braces and Supports; and I do hereby declare that the following is a full, clear, and exact description thereof.

10 My invention relates to devices for sustaining the covers of boxes, particularly cigar-boxes, in an open position and for relieving the strain incident to the handling of said boxes in such condition; and it consists in certain 15 peculiarities of construction of the device employed by me for this purpose, as will be fully set forth hereinafter and subsequently claimed.

20 In the drawings, Figure 1 is a perspective view of one corner of a cigar-box with my improved device attached thereto. Figs. 2 and 3 are perspective views of my said device. Fig. 4 is a plan view of the blank from which my device is made.

25 The especial object of my present invention is to provide a device that will brace and strengthen the connection between the box and its cover and enable the latter to be opened to practically its full extent, so as to lie back 30 nearly flat, and hence so that the usual number of boxes of cigars may be exposed in an ordinary show-case and with the covers of said boxes open and visible from the top and front of the case, and so that any box may be lifted 35 by its cover by the hand of the dealer and carried over the other boxes in the case in the ordinary manner without disturbing said other boxes and without the danger of the weight of the cigars in the box causing the 40 cover to break off.

A further object of my said invention is to enable the said brace to always remain in place without any manipulation or adjustment, whether the box is open or closed, until 45 the cigars are all removed from said box, undisturbed by the opening or closing of said cover, whereby the said device is equally well adapted to be applied to boxes in private houses or elsewhere, which boxes are kept 50 closed except when one or more cigars are to be taken therefrom.

Referring to the drawings, A represents the

end of an ordinary cigar-box, B the back of the said box, and C the cover, the latter being secured to said back in the ordinary way by the usual pasted hinge, of paper or other thin fabric. In handing about a box of cigars by the cover it not infrequently happens that this pasted hinge gives way and the heavy box falls to the floor, thus destroying or injuring the contents. To guard against this and at the same time to enable the box-cover to be opened back nearly flat and closed at will without any manipulation of the strengthening-brace, I have constructed the latter as shown in the accompanying drawings, the inner side of the brace being shown in Fig. 2 and the outer side being shown in Figs. 1 and 3, said views showing the brace D attached and detached, respectively. The brace D is preferably stamped or otherwise formed out of a single thin piece of sheet metal—such as brass, iron, or tin-plate—and is entirely flat with the exception of the inturned slightly-oblique edge a, forming the support of the cover C, and the inturned vertical strip b and corresponding outturned vertical strip c. These strips are formed by making a vertical cut in the blank shown in Fig. 4 on the central vertical line d e and a horizontal cut on the horizontal line f g and then bending the strip b inwardly on the dotted vertical line g h and the strip c outwardly or in the opposite direction on the dotted vertical line f i. The oblique supporting edge a is formed by bending that portion of the blank on the dotted oblique line j k inwardly or so that it will project in the same direction as the strip b. By constructing my device in this manner there is practically no waste of material and a great number of these braces may be formed from a single sheet of metal.

When my device is to be applied to a cigar-box, the cover C is raised and the device slipped to place in the rear right-hand corner of the box, with the back of the box received in the vertical open slot between the strips b and c, the outer face of the brace D coming against the inner surface of the end piece A of the box, and the inner face of the strip b being against the inner surface of the back B of the box, while the inner face of the strip c is against the rear outer edge of the end piece A and the supporting edge a beneath the

cover C, all as indicated by the perspective view Fig. 1. When my device is applied in this manner, (which can be very quickly done and without disturbing the cigars in the box,) the cover C can be closed at any time, and again opened without handling or moving the brace D, and this is a great advantage. If it is desired to support the cover at a more elevated angle, of course this can be done by raising the brace D; but one of the chief advantages of my device lies in enabling the cover to open back nearly flat, and hence the brace would not need to be disturbed after its first adjustment until the box is empty, when it can be quickly removed and applied to another box.

Having thus described my invention, what I claim as new, and desire to secure by Letters Patent, is—

1. A box-cover brace and support, comprising a plate having a slotted lower portion for engagement with the vertical walls of a box, and an outwardly-projecting upper portion bent inwardly at its lower edge only, whereby the cover of the box may be opened out and supported on said bent edge, and closed independently of manipulation or movement of said cover-support.

2. A box-cover brace and support, comprising a sheet-metal plate having a vertically-slotted lower portion, with strips of the metal bent in opposite directions on each side of said slot, and an outwardly-projecting upper portion having its lower edge bent inwardly, on a slightly-oblique upward line, the said plate being otherwise all in the same plane.

3. A box-cover brace and support, comprising a flat metal Γ -shaped plate having a vertical slot in its upright portion, with the edges of the plate at each side of said slot bent in opposite directions, and with the lower edge only of the horizontal portion bent inwardly to form a support, whereby, when the brace is in place upon a box, the cover of the latter may be opened out and supported on the said support, or closed, without manipulation or disturbance of position of said brace.

In testimony that I claim the foregoing I have hereunto set my hand, at Milwaukee, in the county of Milwaukee and State of Wisconsin, in the presence of two witnesses.

NIS S. NISSEN.
